UNITED STATES PATENT OFFICE.

CARL RUDOLPH SCHULTZ, OF MURRAY HILL, NEW JERSEY.

SIPHON-COLLAR.

No. 821,437.

Specification of Letters Patent.

Patented May 22, 1906.

Application filed January 22, 1906. Serial No. 297,194.

To all whom it may concern:

Be it known that I, CARL RUDOLPH SCHULTZ, a citizen of the United States, and a resident of Murray Hill, in the county of Union and State of New Jersey, have invented 5 a new and Improved Siphon-Collar, of which the following is a full, clear, and exact description.

My invention relates to siphon-collars, my 10 more particular object being to provide a two-part collar so arranged as to distribute mechanical strains upon the bottle-neck to better advantage, thereby avoiding any danger of breaking.

Reference is to be had to the accompanying drawings, forming a part of this specification, in which similar characters of reference indicate corresponding parts in both figures.

Figure 1 is a fragmentary elevation, partly 20 in section, showing the upper end of a bottle provided with a siphon of ordinary construction connected thereto by means of my improved siphon-collar; and Fig. 2 is a perspective view of the two halves of the collar separated from each other.

The body of the bottle is shown at 3 and is provided with a frusto-conical neck 4, having 25 an annular bead 5 encircling the same and integral therewith. The two halves or members 6, together constituting the collar, are each provided internally with an arcuate groove 7 and externally with a flange 8. Each half 6 is provided externally with a thread 9. A cap 10, of metal, threaded internally, as shown, screws upon the thread 9 and forces a gasket 11 downwardly upon the 35 top of the bottle-neck, as indicated in Fig. 1. A valve 12, mounted upon a valve-stem 13 and retained in normal position by a spring 40 14, is of the usual construction. The siphon-head is shown at 15, and the movable handle at 16. The latter is used for moving the valve-stem 13, thereby opening the valve 12. The spout is shown at 17 and is of the usual 45 construction.

I find that in siphons of the kind heretofore used the collar being mounted at a comparatively high point upon the bottle-neck exerts a considerable strain upon the neck 50 and is liable to cause the latter to break whenever the apparatus is subjected to any considerable jar. Upon this account I lo-

cate the annular bead 5 at a little distance from the upper end of the frusto-conical neck 4. The two halves 6 are placed in juxtaposition upon opposite sides of the neck, the arcuate groove 7 in each half fitting neatly upon a portion of the annular bead 5. The two halves may for convenience be gripped in a vise until the cap 10 is screwed into position. This being done, the two halves may receive no further attention. The pressure exerted upon the threads 9 by the cap 10 is such as to prevent the displacement of the two halves 6, for the reason that neither 60 groove 7 can leave its portion of the bead 5.

The upper end of the body 3 where it merges into the lower end of the frusto-conical neck 4 is nearly always made of comparatively thick glass, and being a small distance away from any part presenting an edge its annealing is nearly always better. Upon this account it is much more difficult, other things being equal, to break a bottle-neck at the point represented by the annular bead 5. 70 The bead itself though integral with the bottle-neck serves to some extent as an encircling band and still further strengthens the neck at this point. The two-part siphon-collar by distributing the strain not only upon 75 the annular bead 5, but also in a measure throughout the substance of the glass immediately adjacent thereto, prevents the possibility of undue breakage in case any part of the apparatus should receive a jar or blow. 80 85

Having thus described my invention, I claim as new and desire to secure by Letters Patent—

1. In a device of the character described, the combination of a siphon-collar made in 90 halves, each half being provided internally near its bottom with an arcuate groove for engaging an annular bead upon a bottle, each half being further provided with a thread and with an annular bead intermediate of said 95 thread and the approximate position of said arcuate groove, and a siphon-head provided with a cap threaded internally for the purpose of engaging the threads of said halves.

2. A device of the character described, 100 comprising a siphon-collar made in halves, each half being provided internally adjacent to its lower edge with an arcuate groove for engaging a bead upon a bottle, and being

provided externally with a semicircular bead and with a semicircular shoulder bounding said bead, each of said halves being provided with a thread, and a siphon-head threaded internally for engaging said threads of said halves, said siphon-head being provided with a surface for engaging said shoulders.

In testimony whereof I have signed my name to this specification in the presence of two subscribing witnesses.

CARL RUDOLPH SCHULTZ.
